W. DOUCETTE.

DRINKING FOUNTAIN.

APPLICATION FILED JUNE 16, 1917.

1,336,401.

Patented Apr. 6, 1920.

*Inventor:
William Doucette
by Edwin T. Lure
Atty.*

UNITED STATES PATENT OFFICE.

WILLIAM DOUCETTE, OF REVERE, MASSACHUSETTS.

DRINKING-FOUNTAIN.

1,336,401.

Specification of Letters Patent.

Patented Apr. 6, 1920.

Application filed June 16, 1917. Serial No. 175,179.

To all whom it may concern:

Be it known that I, WILLIAM DOUCETTE, of 5 366 Winthrop avenue, town of Revere, county of Suffolk, and State of Massachusetts, have invented an Improvement in Drinking-Fountains, of which the following description, in connection with accompanying drawings, is a specification, like characters on the drawings representing like 10 parts.

This invention relates to drinking fountains, more particularly to the so called public bubble drinking fountains and its primary object is the attachment thereof to existing faucets or the like without necessitating the replacement of said faucet with special fixtures. In addition, the invention has for its object the use of both the faucet and the drinking fountain alternately without detaching or removing the latter from 15 the former.

In order to illustrate my invention I have shown in the accompanying drawing one embodiment thereof wherein;

25 Figure 1 is a plan of my invention illustrating the application thereof to a faucet.

Fig. 2 is a central vertical section on line 2—2 of Fig. 1.

Fig. 3 is a central vertical section on line 3—3 of Fig. 1 with certain parts in a different position hereinafter described.

30 The terms employed herein are used in the generic and descriptive sense and therefore are not primarily intended as terms of limitation.

In the drawing 10 represents a split collar or the like adapted to be clamped to the ordinary straight spout faucet by the screw through the ears 11 and is provided at its 40 lower end with a screw threaded portion 12. The member just described is in the nature of an adapter for use on faucets not provided with the standard coupling thread usually employed for the attachment of filters, 45 hose pipes, couplings or other devices which it is desired to attach to such a faucet.

A nut 15 swiveled upon the shouldered sleeve 16 is designed to be screwed to the screw threaded portion 12 or to perform the 50 same function with respect to a faucet already provided with the standard screw-threaded portion. A washer 17 may be employed between the enlarged head 18 on the sleeve 16 and the adapter above de-

scribed or between the faucet and sleeve as 55 the case may be.

The sleeve 16 is integral with or secured to a cap or head 19 having a screw threaded portion 20. The said sleeve 16 is provided with a central bore 21 and the lower end 60 of said sleeve projects for a short distance within the head 19 and may be opened at the lower end or if closed as shown herein orifices 22 are provided through the said projecting portion in order that water entering 65 said central bore 21 may find entrance to the interior of the said head 19. A filter, filter screen 18' or the like is preferably located interiorly of the top of the cap or head 19 in order that large particles or 70 foreign substances may be prevented from passing through to the bubble head or through the valve seats hereinafter described.

Screw threaded to the portion 20 is a 75 cage, or casing, 24 having a substantially large central bore 25 and a reduced nozzle having a central bore or discharge orifice 26. At the junction between the bores 25 and 26 I preferably provide a frustoconical 80 valve seat 27 adapted to coöperate with a correspondingly tapered seat 28 upon a cylindrical valve 29.

The valve 29 is provided also with an upper conical valve seat 30 adapted in its 85 operation to coöperate with a stationary valve seat 32 vertically slidable within the bore or chamber 25. The latter valve seat 32 is adapted to be held in position and in engagement with the seat 30 by means of 90 a coil spring 34 bearing thereagainst and against a ring-like collar 35 inserted in the head 19 for the purpose and which is also adapted to maintain the filter screen 18' in position. Normally the said valve is 95 securely held between the valve seats 27 and 30 and rotatable thereon without reference to any other securing means. A washer 31 at the edge of the member forming the valve seat 30 prevents the passage of water 100 between the same and the casing 24.

The upper surface of the valve seat 30 provides a wall to form with the cap or head 19 an upper chamber located near the top of the head 19. In order to permit the 105 passage of water from such chamber to the various parts I provide through the said seat 30 a single orifice 36 located substan-

tially between the center or axis of said valve seat and the periphery. The valve 29 is provided with two passages each adapted alternately to register with the orifice 36 by reason of their location in different planes. One of these passages is adapted to communicate directly with the bubble part of the fountain while the other is adapted to form a passage between the head 19 and the 10 nozzle passage 26. Herein, for example, I provide the valve 29 with the passage 38 adapted to communicate with the orifice 36 when the valve is swung in one position about its seat. This latter passage leads off 15 at right angles to the axis of the valve and is in direct communication with a pipe 39 screw threaded at 40 into the side of said valve 29. A passage 42 adapted to communicate with the orifice 36 is spaced circumferentially of the passage 38 and is directed clear through said valve at an inclination that will bring the bottom of said passage substantially central with the bore 26. 20

The pipe 39 leads from said valve at right 25 angles thereto and is preferably looped downward and then upward at a short distance from the valve 29 and on the upper end thereof I provide a bubble head 45 at the top of which is a cap 47 having there- 30 through a comparatively large size orifice 48 through which water is adapted to pass in the form of small ebullitions or a bub- 35 bbling stream which is adapted to be easily reached by the lips of the person who desires a drink of water.

Said pipe 39 forms a lever or handle adapted to be grasped by the operator to turn the valve 29 so that the passage 38 may be placed in communication with the 40 orifice 36 to permit water to flow there- through and through the pipe 39 to the head 45 from whence it will be discharged through the orifice 48 as described. When this occurs the passage 42 is not in com- 45 munication with the orifice 36 and all the water is projected into the drinking fountain portion. If, however, the operator will now rotate the valve until the passage 42 is in communication with the orifice 36 the pas- 50 sage 38 is cut off from the latter and water will flow through the orifice 36 the passage 42 thence to the bore 26 to be projected from the faucet or nozzle in the usual manner. When the valve 29 is turned so that neither 55 passage 38 or 42 communicates with the orifice 36 the blank surface of said valve so presented entirely shuts off all flow through said orifice.

In order that the said passages 38 or 42 60 and a blank portion of the valve may be permitted to register with the orifice 36 the casing or cage 24 is cut away or slotted semi- circumferentially for a distance correspond- 65 ing to the entire distance of movement re- quired of the pipe 39 in order to bring the

said passages or the blank space to register with said orifice when the said pipe 39 en- gages the extreme end walls of the said slot and prevent further movement of the valve 29 in that direction. 70

Therefore the casing 24 need not be in- closed and may be in the nature of a cage with merely a supporting means for the valve seat 27 and to provide a nozzle por- tion and the outlet passage 26. It has been 75 found sufficient that the valve be provided only with the ample bearing surfaces which I herein combine with the respective valve seats. Therefore the said valve 29 need not be provided with packing devices or the like 80 or any other means to prevent water from passing the point of valve support formed by the respective seats held in proper rela- tive engagement by the coil spring 34 press- ing the valve seat 32 against the upper seat 85 30 on the said valve 29.

By means of my invention I provide what has been termed a bubble drinking fountain adapted in its use and application to be utilized as a drinking fountain and at the same 90 time permit the faucet to be used in the well known manner. The faucet may be provided with the usual shut off valve or the like which it is unnecessary herein to de- 95 scribe or illustrate any further than indicated.

In order that excessive water pressure may not be projected into the bubble head 45 I provide at the lower portion thereof a pressure reducing valve 55 consisting of a 100 plug like member forced into the bore at the bottom of the said bubble head and pro- vided with a plurality of smaller orifices 56 drilled longitudinally thereof. Axially of the valve I provide a screw threaded bore 105 57 adapted to be engaged by the screw 58 having an enlarged head 59 and by rotating the said screw the same will move up or down carrying with it said head 59. If said head be brought away from the orifices 56 110 a greater water pressure will be had and if said screw be rotated to reduce the distance between the said valve 55 and said head it will cut off to a very large measure the amount of the water and therefore the force 115 of the same as it enters the bubble head. In this manner I can reduce the actual force of water entering the aforesaid bubble head and therefore produce just the desired bub- 120 bbling effect above the orifice 48 and prevent projecting a stream of water into the face of the user if the faucet is turned fully on. On the other hand the water pressure or stream is not materially reduced in force as it flows through the passage 38 and through the nozzle bore 26 all for ordinary purposes. Likewise it will be noticed that when the bubble fountain is not in use or when the passage 38 communicates with the orifice 125 36 the head 45 and pipe 39 is swung back to 130

one side of the faucet where it is entirely out of the way, and all the normal functions of a faucet are retained.

I have described herein one embodiment 5 of my invention; but it is to be understood that the latter is not essentially limited to the specific details of construction and organization of said embodiment, since the same may be varied without departing from 10 the proper scope of the claims.

Claims.

1. In a device of the character described, a casing adapted to be attached to an ordinary water faucet, said casing being provided with coupling means therefor and having an inlet therethrough and an outlet in alinement with said inlet and a bearing seat adjacent to the latter, an independent valve seat movable in axial alinement with 15 said inlet and said outlet and having a passage therethrough between the axis thereof and its periphery, a rotatable valve bearing wholly on the bearing seat on said casing and on the said independent valve seat and 20 wholly supported and rotatable thereon, said valve having one passage adapted at times to aline with the passage in said valve seat and with said outlet and having another passage adapted at other times to aline with 25 said passage through said independent valve seat and adapted to direct water transversely thereto, a pipe provided with a drinking head and connected with said valve to communicate with its transverse passage 30 and extending transversely to the valve to rotate the same.

2. In a device of the character described, a casing adapted to be attached to an ordinary water faucet, said casing being provided with coupling means therefor and having an inlet therethrough and an outlet in alinement with said inlet and a bearing seat adjacent to the latter, an independent valve seat movable in axial alinement with 40 said inlet and said outlet and having a passage therethrough between the axis thereof and its periphery, a rotatable valve wholly supported by and rotatable on said valve 45 seats, said valve having one passage adapted at times to aline with the passage through said independent valve seat and with said outlet and having another passage adapted at other times to aline with the passage 50 through the independent valve seat and adapted to direct water transversely through the valve, a pipe connected to said valve to communicate with its transverse passage and extending transversely to the valve to 55 rotate the same, a drinking head on said pipe and having an opening through which a jet of water may pass, a pressure reducing device in said head and a spring to force said independent valve seat toward the casing 60 valve seat to wholly support the valve 65 rotatably therebetween.

seats, said valve having one passage adapted at times to aline with the passage through said independent valve seat and with said outlet and having another passage adapted at other times to aline with the passage through the independent valve seat and adapted to direct water transversely through 70 the valve, a pipe provided with a drinking head and connected with said valve to communicate with its transverse passage and extending transversely to the valve to rotate the same, and a spring to force said independent valve seat toward the casing valve seat to wholly support the valve rotatably 75 therebetween.

3. In a device of the character described, a casing adapted to be attached to an ordinary water faucet, said casing being provided with coupling means therefor and having an inlet therethrough and an outlet in alinement with said inlet with a bearing seat adjacent to the latter, an independent 80 valve seat movable in axial alinement with said inlet and said outlet and having a passage therethrough between the axis thereof and its periphery, a rotatable valve wholly supported by and rotatable on said valve 85 seats, said valve having one passage adapted at times to aline with the passage through said independent valve seat and with said outlet and having another passage adapted at other times to aline with the passage 90 through the independent valve seat and adapted to direct water transversely through the valve, a pipe connected to said valve to communicate with its transverse passage and extending transversely to the valve to rotate the same, a drinking head on said pipe and having an opening through which a jet of water may pass, a pressure reducing device in said head and a spring to force said independent valve seat toward the casing valve seat to wholly support the valve 95 rotatably therebetween.

In testimony whereof I have signed my name to this specification.

WILLIAM DOUCETTE.
